CLAIM

The ornamental design for a simulative shape matching toy, as shown and described.

[21] Appl. No.: 857,446

DESCRIPTION

[22] Filed: Apr. 22, 1986

FIG. 1 is a front elevational view of a simulative shape matching toy showing our new design;
 FIG. 2 is a rear elevational view thereof;
 FIG. 3 is a side elevational view thereof, the side opposite being substantially a mirror image;
 FIG. 4 is a top plan view thereof; and,
 FIG. 5 is a bottom plan view thereof.
